UNITED STATES PATENT OFFICE

ERIC ALEXANDER OLLARD, OF LONDON, AND ERNEST YEOMAN ROBINSON, OF MANCHESTER, ENGLAND, ASSIGNEES, BY MESNE ASSIGNMENTS, TO ASSOCIATED ELECTRICAL INDUSTRIES LIMITED, A BRITISH JOINT STOCK COMPANY

VACUUM ELECTRIC TUBE

Application filed May 15, 1924, Serial No. 713,435, and in Great Britain June 2, 1923.

This invention relates to vacuum electric tube devices and like evacuated apparatus which are in part metallic, such for example as vacuum electric discharge tubes having envelopes which are partly formed of metal and which may serve as the anodes of the devices.

According to the invention the metallic portion of such a device is produced wholly or in part by electro-deposition. It preferably consists of copper. In the preferred form it consists of a copper tube which is closed at one end and the open end thereof is fused to a vitreous portion so as to provide a gas-tight joint. The tube is produced by the deposition of copper upon a mandrel or former which is preferably rotated at a high speed during the deposition in order to produce a dense layer of copper. For example in the preferred method the mandrel is rotated so that its surface velocity is about 1000 ft. per minute.

In carrying out the invention according to one method, a mandrel of suitable shape is first made, the exterior of which corresponds to the interior of the metallic casing to be produced. This mandrel may be made of bronze or steel. In the latter case it must first be copper plated by the usual process in a cyanide bath. Preferably, a jet of electrolyte is directed on to the rotating mandrel during the plating. Before placing the mandrel in the plating bath, the mandrel is prepared for a non-adhesive deposit by any of the ordinary methods, such, for example, as by immersion in potassium sulphide. The copper is deposited on the mandrel from an electrolyte of acid copper sulphate until the required thickness is obtained. It is then re-

moved from the mandrel by spinning or other suitable means; for example the mandrel may be made slightly conical to facilitate removal of the case or it may be dipped before plating in a fusible conducting material such for example as Woods metal or wax graphite mix-

ture which forms a thin coating over the mandrel, which coating will flow when the mandrel is heated to remove the copper case. In this case the mandrel must be constructed slightly smaller than the required final size. The open end of the copper tube is then sealed in any manner to a vitreous container which preferably consists of a glass tube closed at one end and provided with a re-entrant tube carrying the necessary seals for the various lead-in wires of the device. In one method the tube is sealed direct to the vitreous container. The copper tube may be greater or smaller in diameter than the glass and may be sealed either inside or outside the glass or alternatively it may be fused into the glass. The sealing of the copper tube to the glass tube may be facilitated by the use of borax as a flux during the fusion process. It may preferably be given a feather edge since it is found that the joint is more satisfactory in this case, and it facilitates the fusion of the copper tube into the glass. This feather edge may be produced, for example by grinding or spinning down the end of the copper tube or it may be produced by drawing the mandrel up from time to time in the plating bath. The copper may be made more homogeneous by working it, for example, by spinning it after it has been deposited.

Alternatively, the copper tube may be welded to a ring of material having a coefficient of expansion approximately equal to that of the glass employed, which ring is then sealed into or on to the vitreous container. Such a ring may be made in a known manner, for example, of nickel steel, which may be coated with copper or it may consist of platinum.

Various means have been proposed for fusing the copper into intimate contact with the glass. In one method a wax or fusible metal former which is made suitably conducting is attached to the open end of the glass tube which forms the vitreous part of the con-

tainer. The end of the glass tube, for example a length thereof of about 2 cm. is first coated with an adherent deposit of gold, for example, by painting on a solution of gold 5 chloride and heating and so producing gold. Several such coatings of this may be applied, or the tube may be rolled in gold leaf or a combination of both methods may be adopted and the gold then fused into the glass. 10 The copper case is then deposited over the former and over the end of the vitreous tube; it is then fused to the glass by heating which removes the gold by alloying it with the copper and fuses the copper direct to the glass. 15 The case may be deposited in two stages and the fusion process may be carried out between the stages so that during the fusion process the copper deposit is relatively thin. In alternative methods a portion of the 20 vitreous container is first given a copper coating which is fused thereto in the manner described above. A former, which is a shape to aid in the construction of the device and which is preferably of fusible alloy or wax 25 is then attached to the open end of the tube the surface of which is rendered conducting, and the former is brought into contact with the copper band and deposition continued in the acid copper sulphate. Thus deposition 30 will then take place over the sealed-in band of copper and also over the former, and hence will be perfectly continuous over its surface. After deposition to the desired thickness the former is removed by warming. If desired 35 the thickness of deposition may be varied by raising or lowering the mandrel in the electrolyte. In another method a thin copper tube which is closed at one end and which may be formed in the manner described in 40 the first modification of this invention, is placed on the open end of the glass so that this open end touches the fused-in copper band. Preferably, it may also overlap and be sprung on to this fused-in copper band 45 and a further layer deposited over the case so formed which layer is perfectly continuous and provides a container suitable for being highly exhausted. It is desirable that the copper deposit which is sprung on to the 50 fused-in copper band should be very thin. It may therefore preferably be filled during the deposition process with a fusible substance in order to give it rigidity and hold it firmly on to the vitreous portion of the glass. 55 The copper anode or envelope produced according to the invention may further be coated with a metal such as tin to render it less porous.

In the accompanying drawings constituting a part hereof and in which like reference characters designate like parts,

Fig. 1 is a vertical sectional view partially in elevation of a discharge tube embodying the principles of the invention, and

Fig. 2 is a sectional view showing a vac-

uum tube in course of manufacture, in accordance with a modification of our invention, in which the metallic anode is flared near its junction with the glass of the tube wall.

Fig. 3 is a similar view of a modification 70 of our invention in which the metallic anode and the glass portion of the tube wall are of approximately the same diameter.

Fig. 4 is a similar view of a modification 75 of our invention in which the anode is first formed as a thin metallic shell and then sealed to the exterior of the glass wall portion.

Fig. 5 is a similar view of a modification 80 in which a thin shell is first fused to the glass and the metallic anode then forced over the metal shell and the whole structure thickened by electro-deposition.

Fig. 6 is a similar view of a modification 85 in which the glass portion is provided with a copper surface near its edge and a fusible mandrel set in position therein so that the metallic anode may be formed by electro-lytic-deposition upon the latter.

Referring to Fig. 1 of the drawings the tube 90 therein illustrated comprises in general a copper anode 1 constructed as hereinbefore described, a cathode 2 and a vitreous envelope portion 3. The copper anode 1 is substantially cylindrical and closed at one end as shown and the other end thereof is enlarged as indicated at 4 to a diameter corresponding to that of the vitreous portion 3. The edge of the enlarged portion of the anode is made thin or wedge-shaped as indicated at 5 to facilitate the sealing thereof to the vitreous portion 3. The cathode is supported upon a re-entrant part 6 of the vitreous portion 3 and comprises two concentric tungsten tubes, 100 the outer of which only is visible in the figure. The two cathode tubes are supported by means of tungsten or molybdenum stems 7 welded thereto at one end and at the other end brazed by means of copper into holes formed in supporting members 8 and 9. The supporting member 9 comprises a steel tube which carries the stems 7 which are attached to the outer of the cathode tubes. The supporting member 8 comprises a tube having 105 lugs which are provided with holes which accommodate the stems 7 attached to the inner of the cathode tubes. The support 8 is carried by and insulated from the supporting member 9 by means of a steatite separator 110 a portion of which is indicated at 10. Shields for confining the tube discharge to the inter-electrode space are indicated at 11 and 12, these shields being supported from the cathode members in any convenient manner. The electrode support 9 is riveted or otherwise attached to a plurality of arms 13 which are secured to the re-entrant part 6 of the vitreous portion 3 by means of clips 14. The re-entrant part 6 is sealed to the portion 3 at 115 120 125 130

Fig. 2 is a sectional view showing a vac-

in the well known manner. The anode 1 is sealed to the vitreous portion 3 in the manner described hereinbefore.

Instead of the end of the copper anode 1 being enlarged to the diameter of the vitreous portion 3 as illustrated in Fig. 1 it may be flared as indicated at 16 in Fig. 2 and the end of the vitreous portion 3 to which the anode is attached may be tapered as indicated at 17 in Fig. 2. Or as illustrated in Fig. 3 the anode 1 and vitreous tube 3 may be of substantially the same diameter, one fitting within the other as illustrated in Fig. 3 wherein the vitreous portion 3 is sealed within the end of the anode 1. Alternatively, the anode 1 may be sealed within the end of the vitreous portion 3 or the edge of the anode 1 may be fused directly into the edge of the vitreous portion.

Referring to Fig. 4 which illustrates a modified construction the anode 1 comprises in the first stage a thin copper shell which may be formed for example by spinning or by electrolytic deposition. Such thin shell is fused or sealed to the vitreous portion 3 of the device and after fusion further deposition of copper is effected to thicken the walls of the anode.

Fig. 5 illustrates the method wherein the vitreous portion 14 is provided with a comparatively thin copper surface as indicated at 18 which is fused into the vitreous material. A comparatively thin copper anode shell is then forced over the end of the vitreous portion 3 carrying the deposit 18. Finally, further deposition of copper is effected until the required thickness is obtained, the copper thus further deposited also providing a seal between the anode 1 and the copper coating 18, that is to say, between the anode 1 and the vitreous portion 3 of the device.

Referring to Fig. 6 which illustrates another method connecting the anode portion 1 to the vitreous portion 3 the latter is provided with a copper surface 19 at its edge in the manner described in connection with Fig. 5. A fusible mandrel the surface of which is made electrically conductive in the manner hereinbefore described is then fixed to the vitreous container and the copper anode is deposited over both the mandrel and the band of copper deposition 19. One end of the mandrel is indicated by dotted lines at 20. When the deposition is sufficiently thick the mandrel is removed by melting it as described.

In Figs 4, 5 and 6, the thickness of the copper shells 1 and the deposits 18 and 19 is exaggerated for clarity of explanation. Actually such shells and deposits will be made as thin as practically possible.

Various modifications can be made without departing from the scope of the invention.

We claim as our invention:—

1. In the method of manufacturing vacuum electric tubes, the steps which comprise

forming a portion of the envelope from a vitreous material and producing a metallic portion of the envelope by attaching to said vitreous portion a former having a conductive surface and electrolytically depositing 70 said metallic portion on said former rotated at high speed in an electrolyte.

2. In the method of manufacturing vacuum electric tubes having a vitreous portion and a copper portion, the steps which comprise directly fusing a thin walled copper envelope portion to the vitreous envelope portion and electrolytically depositing copper on the copper envelope portion to increase the thickness of its wall.

3. In the method of manufacturing vacuum electric tubes having a vitreous portion and a copper portion, the steps which comprise providing a coating of copper on that part of the vitreous envelope portion to which the metallic envelope portion is to be united, fusing said coating to the vitreous portion, fitting a relatively thin copper envelope portion to the vitreous portion to partially overlap the fused coating thereon, and electrolytically depositing copper over the metallic portion and over the exposed portion of the fused coating to increase the wall thickness of the copper portion and also provide a hermetic seal between the copper and vitreous 65 portions of the envelope.

4. In a vacuum electric tube device, a vitreous envelope portion, a coating of copper upon a portion thereof, and a metallic envelope portion fused thereto.

5. In the method of manufacturing vacuum electric tubes, the step which comprises forming a portion of the envelope from a vitreous material and producing a metallic portion of the envelope by attaching to said vitreous portion a former having a conductive surface and electrolytically depositing 105 said metallic portion on said former.

6. In the method of manufacturing vacuum electric tubes having a vitreous portion and a metallic portion, the steps which comprise fusing a coating of copper to the vitreous portion, inserting a removable mandrel in said vitreous portion and electrolytically depositing a copper envelope portion on the 115 removable mandrel and upon the fused copper coating.

7. In the method of manufacturing vacuum electric tubes, having an envelope comprising a vitreous portion and a metallic portion, the steps which comprise providing a coating of copper on the vitreous portion, electrolytically depositing the copper envelope portion on a removable mandrel and upon the said coating of copper, and fusing 120 the junction between the vitreous portion and said copper coating.

8. In the method of manufacturing vacuum electric tubes having an envelope comprising a vitreous portion and a metallic por- 130

tion, the steps which comprise providing a coating of copper on the vitreous portion, electrolytically depositing a thin copper envelope portion on a removable mandrel and upon the said coating of copper, fusing the junction between the vitreous portion and said copper coating and electrolytically depositing copper upon the copper envelope and over said fused junction.

10 In testimony whereof, we have hereunto subscribed our names this 28th day of April 1924.
